UNITED STATES PATENT OFFICE.

SAMUEL GISSINGER, OF PITTSBURG, PENNSYLVANIA, ASSIGNOR TO JOHN H. NOBLE, OF SAME PLACE.

LOCK-NUT.

SPECIFICATION forming part of Letters Patent No. 298,842, dated May 20, 1884.

Application filed September 13, 1883. (No model.)

To all whom it may concern:

Be it known that I, SAMUEL GISSINGER, of Pittsburg, in the county of Allegheny and State of Pennsylvania, have invented a new and useful Improvement in Lock-Nuts; and I do hereby declare the following to be a full, clear, and exact description thereof.

My invention relates to an improvement in lock-nuts; and it consists in a nut having a space or cavity intersecting the bolt-hole and so situated as to form a spring lock-nut.

I will now describe my invention so that others skilled in the art may manufacture and use the same, reference being had to the accompanying drawings, forming part of this specification, in which—

Figure 1 is a perspective view of one form of my improved nut. Fig. 2 is a vertical sectional view of the same through the line $x-x$ of Fig. 1. Fig. 3 is a vertical sectional view of the same through the line $y-y$, Fig. 1. Fig. 4 is a perspective view of a modified form of my improvement. Fig. 5 is a vertical sectional view of the same. Fig. 6 is a perspective view of a modified form, the nut being in separate pieces or plates united together. Figs. 7, 8, and 9 are views of another modified form having an interior cavity, the two portions of the nut being joined by radial grooves and projections. Fig. 10 is a horizontal sectional view of a modified form. Fig. 11 is a vertical section through line $x-x$, Fig. 10.

Like letters of reference indicate like parts wherever they occur.

In the drawings, a represents the nut, in which is formed a cavity, c , intersecting the bolt-hole b , as shown in Fig. 1, and being of a greater width than the bolt-hole, and extending through the nut from side to side, so as to form a nut having an upper portion, d , and a lower portion, e , united on two of the sides d . The bolt-hole b , which extends through the upper and lower portion of the nut, is threaded above the cavity and is plain and without threads below the cavity, so that when the nut is screwed on the bolt the upper portion of the nut will be slightly sprung toward the lower portion, and by its elastic resistive force cause a pressure on the face of the threads.

In Figs. 4 and 5 the nut is shown having

cavities extending from each side, the upper and lower leaves or portions being united at the corners. The cavity c may also be annular in form in the interior of the nut around and intersecting the bolt-hole, as shown in Figs. 10 and 11, a boss, f , being formed around the bolt-hole on the exterior surface of the lower or washer leaf, the purpose of the boss being to spring or bend the lower portion of the nut toward the upper face or portion, so as to increase the resistive elastic force.

In Figs. 6, 7, 8, and 9 the nut is shown formed in two or more pieces, which are united or fastened in any convenient manner, as by welding, by a rust-joint, or by riveting; or they may be held in place relatively to each other by making a radial groove or grooves in one face of the upper leaf, and a corresponding projection or projections in the corresponding face of the lower section. A greater amount of spring action may be secured by making the upper leaf or section of steel and the lower leaf or section of iron or brass.

The operation is as follows: The nut being preferably formed of steel or other metal having a certain amount of elasticity, when it is screwed on the bolt the face of the lower portion comes in contact with the fish-bar, and, by the action of the threads of the nut and bolt, the upper portion of the nut is slightly sprung inward toward the lower portion, or where the boss f is formed on the face of the nut below the cavity. Both faces of the nut are sprung toward each other. Owing to the elastic resistive force of the metal, the threads of the nut are kept pressing against the threads of the bolt, which pressure is sufficient to prevent the nut from being loosened by the repeated jarring or jolting of passing trains.

The advantages of my invention are that a simple and effective lock-nut is produced, which is easily applied, and is locked on the bolt without extraneous aid.

I am aware that nuts having an interior cavity are not new, and that nuts having an annular groove around the bolt-hole are not new; but I am not aware that nuts having a cavity intersecting the bolt-hole so as to form a spring lock-nut, the eye of the nut being threaded above the cavity and plain or unthreaded be-

low the cavity, have been known or used prior to my invention thereof.

Having thus described my invention, what I claim, and desire to secure by Letters Patent, 5 is—

1. A nut having an upper threaded portion and a lower unthreaded portion separated by a cavity intersecting the eye of the nut, substantially as and for the purpose specified.
- 10 2. A nut having an upper threaded portion and a lower unthreaded portion separated by

a cavity intersecting the eye of the nut, parts being formed separately and united together, substantially as and for the purpose specified.

In testimony whereof I have hereunto set my hand this 11th day of September, A. D. 1883.

SAMUEL GISSINGER.
